CLAIM

The ornamental design for a multi-compartment roll-up packaging container with cap, as shown and described.

DESCRIPTION

1. Multi-compartment roll-up packaging container with cap
1.1 is a fully unrolled (flat) state, of various roll-up states, perspective view of a multi-compartment roll-up packaging container with cap, showing my new design;
1.2 is a flat front elevational view thereof;
1.3 is a flat rear elevational view thereof;
1.4 is a flat left elevational view thereof;
1.5 is a flat right elevational view thereof;
1.6 is a flat top plan view thereof;
1.7 is a flat bottom elevational view thereof;
1.8 is a partially rolled state, of the various roll-up states, perspective view of the multi-compartment roll-up packaging container with cap shown in Figure 1.1;
1.9 is a partially rolled front elevational view thereof;
1.10 is a partially rolled rear elevational view thereof;
1.11 is a partially rolled left elevational view thereof;
1.12 is a partially rolled right elevational view thereof;
1.13 is a partially rolled top plan view thereof;
1.14 is a partially rolled bottom elevational view thereof;
1.15 is a fully rolled state, of the various roll-up states, perspective view of the multi-compartment roll-up packaging container with cap shown in Figure 1.1;
1.16 is a fully rolled front elevational view thereof;
1.17 is a fully rolled rear elevational view thereof;
1.18 is a fully rolled left elevational view thereof;
1.19 is a fully rolled right elevational view thereof;
1.20 is a fully rolled top plan view thereof; and
1.21 is a fully rolled bottom elevational view thereof.
